(57) **CLAIM**

The design for a detachable electronics bag, as shown and described.

DESCRIPTION

FIG. 1 is an isometric view of the claimed detachable electronics bag, embodying the present design;

FIG. 2 is a front side view thereof;

FIG. 3 is a rear side view thereof;

FIG. 4 is a left side view thereof;

FIG. 5 is a right side view thereof;

FIG. 6 is a top down plan view thereof; and,

FIG. 7 is a bottom up plan view thereof.

The dashed lines in FIGS. 1, 2, 3, 4, 5, 6 and 7 represent stitching. The stippling in the drawings represents texture.
